UNITED STATES PATENT OFFICE.

IRA S. BROWN, OF BRIDGEPORT, CONNECTICUT.

ELECTRIC WRITING-MACHINE.

1,027,984.

Specification of Letters Patent. Patented May 28, 1912.

Application filed May 4, 1910. Serial No. 559,812.

To all whom it may concern:

Be it known that I, IRA S. BROWN, a citizen of the United States, residing at Bridgeport, county of Fairfield, State of Connecticut, have invented an Improvement in Electric Writing-Machines, of which the following is a specification.

This invention relates to writing machine actions and has for its object to provide a simple, durable and inexpensive action, so constructed that a slight depression of a key will place a thrust bar in the path of movement of a rotating impact member whose blow upon the thrust bar causes the thrust bar to actuate the corresponding type bar, thus greatly increasing the speed of the machine and making it easy to operate.

It will of course be obvious that the principle of the invention is applicable, with unimportant changes in the details of construction, to the various types of writing machines now upon the market. In other words, my invention enables me to build electric machines from the parts of ordinary machines by the substitution of certain parts for others but without remodeling the machine or adding greatly to the cost of construction.

With these and other objects in view I have devised the simple and novel electric action of which the following description in connection with the accompanying drawing is a specification, reference characters being used to indicate the several parts.

Figure 1 is a side elevation of my novel action; and Fig. 2 is a partial plan view of a keyboard.

10 denotes framework which may be of any ordinary or preferred construction. In the present instance I have shown Underwood framework.

11 denotes a type-bar, 12 a type-bar link, 13 an operating bar, 14 a thrust bar pivoted thereto, 15 a key bar, 16 a key post and 17 a key.

18 denotes a shaft which carries an impact member 19. It will of course be understood that the special details of construction are unimportant so far as the principle of the invention is concerned. In the present instance I have shown the shaft as provided at each end with a disk 20 and a rod serving as an impact member and extending from disk to disk and rigidly secured thereto parallel with the shaft. Rotary motion at a high speed may be imparted to the shaft

and impact member in any preferred manner, as by means of a belt 21 extending from an electric motor (not shown) and passing over a pulley 22.

Each type-bar 11 is pivoted to the framework as at 23 and is provided with a slot 24 which is engaged by a pin 25 projecting from a type-bar link 12. The rear end of each operating bar 13 is pivoted to the framework as at 26. Each type-bar link is pivoted to the framework as at 27 and is provided with an arm 28 which is pivoted to the corresponding operating bar at approximately its mid-length as at 29. In ordinary machines the member I have termed an operating bar extends to the forward end of the machine and is called a key bar. In my present machine each key bar is pivoted to the framework as at 30, and the forward end of the corresponding operating bar terminates contiguously to the rear end of the key bar. The forward end of each key bar terminates in a key post carrying a key, and at the rear end of each key bar is an upwardly extending arm 31 which normally engages a stop pin 32 and which carries a pin 33 which is adapted to engage the thrust bar, indicated by 14. The lower end of the thrust bar is pivotally connected to the forward end of the operating bar and the thrust bar is held in engagement with pin 33 by means of a spring 34 which returns both the thrust bar and the key bar to their normal position after each actuation. In the present instance I have shown the thrust bar as connected to the operating bar by means of a slot 35 which receives a pin 36 projecting from the operating bar, the object being to provide a pivotal connection without positively connecting said bars together. At the upper end of the thrust bar is a lug 37 which is adapted to be engaged by the impact member.

The operation is as follows: The effect of a quick blow by the finger of the operator upon a key is to depress the key to the limit of its movement, which is determined by the engagement of the key bar with a stop pin 38. The key bar is oscillated on its pivot and the thrust bar is swung forward by the engagement of pin 33 therewith, placing lug 37 on the thrust bar in the path of movement of the impact member against the power of spring 34. The action of the impact member when it engages the lug on the thrust bar is to swing the thrust bar

downward and forward, as indicated by dotted lines, until the impact member passes out of engagement with the lug, when the thrust bar is returned to its normal position by spring 34. The downward movement of the thrust bar carries the operating bar downward, which in turn, by means of the type-bar link, swings the type-bar into the printing position, as indicated by dotted lines. The instant the blow of the type-bar is struck, said bar and the operating bar are returned to their normal positions by means of a spring 43. The type-bar as it drops back to its normal position is stopped by a pad 42 upon which it normally rests.

Having thus described my invention I claim:

1. In a typewriting machine, the combination of an operating bar, an impact member, a thrust bar pivotally connected to the operating bar, a key bar provided with a laterally projecting pin for engaging the thrust bar to place the same in the path of the impact member, and means for moving the thrust bar out of the path of the impact member when disengaged from said pin.

2. In a typewriting machine, the combination with a frame, of an operating bar pivoted thereto, a key bar pivoted to said frame and provided with an end arm, an impact member, a thrust bar pivoted to the operating bar, and means carried by said arm for engaging the thrust bar to place the same in the path of movement of the impact member.

3. In a typewriting machine, the combination of an operating bar provided with an end pin, a thrust bar having an end slot engaging said pin, an impact member, and a key bar provided with means for placing the thrust bar in the path of the impact member.

4. In a typewriting machine, the combination of an operating bar, a thrust bar having a direct loose pivotal engagement therewith, an impact member, means for normally retaining the thrust bar out of the

path of movement of the impact member, and a key bar provided with means for engaging the thrust bar to place the same into 50 the path of the impact member.

5. In a mechanism of the character described, the combination with an operating bar having a pin extending therefrom, and a thrust bar having a slot to receive said pin, 55 of a shaft carrying an impact member, a key bar by which the thrust bar is swung into the line of movement of the impact member and a spring for returning the thrust bar to its normal position.

6. In a mechanism of the character described, the combination with an operating bar and a thrust bar connected thereto, of a shaft carrying an impact member, a key bar having an arm carrying a pin engaging 65 the thrust bar to swing it into the line of movement of the impact member and a spring for returning the thrust bar to its normal position.

7. In a mechanism of the character described, the combination with an operating bar and a thrust bar connected thereto, of a shaft carrying an impact member, a key bar acting to swing the thrust bar into the line of movement of the impact member, a 75 spring for returning the thrust bar to its normal position and stops for limiting the movement of the key bar.

8. In a typewriting machine, the combination with a frame, of a type operating bar pivoted thereto, a thrust bar pivotally connected to the operating bar, a rotary impact member, means for rotating said member, a key bar pivoted to the frame and having an end arm, a pin carried by said arm for rocking the thrust bar into the path of the impact member, and a spring connection between the frame and the thrust bar.

In testimony whereof I affix my signature in presence of two witnesses.

IRA S. BROWN.
